UNITED STATES PATENT OFFICE

CLIFFORD E. ANDERSON, OF BRAINERD, MINNESOTA

CAN-TOP LOCK

Application filed July 1, 1929. Serial No. 375,306.

The invention aims to provide an exceptionally simple and inexpensive, yet an efficient and very desirable device for locking the covers of cream and milk cans against accidental removal, for instance if the cans should be tipped over.

Another object is to provide a device of the class described which is normally confined almost entirely within the space surrounded by the usual flared side wall of the cover.

A still further object is to provide a device of the class mentioned in which a single resilient ring serves not only as means for holding the locking bolts projected through the usual openings of the can cover and neck, but also engages the handle of the cover and thereby holds the entire contrivance against accidental loss, even when the cover is detached from the can or the bolts are disengaged from the openings.

Yet another aim is to provide a construction in which sliding of the bolts down the usual flared portion of the cover side wall is instrumental in tensioning spring means which acts to project said bolts through the openings when they reach the latter.

A still further aim is to provide the bolts with teeth which become effective upon slight upward movement of the cover within the neck, to positively hold said bolts against withdrawal until the cover is again forced downwardly.

A still further aim is to provide the bolts of much smaller diameter than the openings through which they are to pass thereby permitting the passage of the conventional seal wire through these openings also, if desired.

With the foregoing and minor objects in view, the invention resides in the novel subject matter hereinafter described and claimed, description being accomplished by reference to the accompanying drawing.

Fig. 1 is a top plan view of a can and its cover, showing the locking device in operative relation therewith.

Fig. 2 is a vertical sectional view on line 2-2 of Fig. 1.

Fig. 3 is a sectional view of the cover and

the locking device showing the bolts in released position.

Fig. 4 is a perspective view showing a different manner of constructing the bolts and a different way of connecting them with the 55 spring ring.

The drawing above briefly described illustrates the preferred forms of construction and while such construction will be herein specifically explained, it is to be understood 60 that within the scope of the invention as claimed, variations may be made.

The numeral 4 of the drawing denotes a conventional milk or cream can whose neck 5 is flared at its upper end as denoted at 6 65 and is formed with diametrically opposed openings 7. 8 has reference to the conventional cover whose continuous side wall 9 is flared at its upper portion as indicated at 10, said flared portion 10 being formed with diametrically opposed openings 11 to register with the openings 7. The usual handle 12 is disposed diametrically and is secured at its ends to the flared portion 11 of the wall 9, the lower side of said handle being usually below 70 the lower edges of the openings 11.

Cans and covers of the type shown and described, are furnished in various sizes but the design in each instance is substantially the same. The improved cover-locking device may be correspondingly furnished in different sizes, the constructions of the several sizes however being substantially the same.

In the form of construction seen in Figs. 85 1 to 3, two locking bolts 13 are provided, said bolts being of cylindrical form and of much less diameter than the openings 7-11, so that while these openings are occupied with the bolts as seen in Figs. 1 and 2, the conventional seal wire (not shown) may also be passed through said openings. A suitable spring wire ring 14 is secured to the inner ends of the bolts 13, said ring being of a 90 diameter substantially equivalent to the smaller diameter of the cover side wall 9 and being adapted to be passed under the handle 12 and to then assume a downwardly bowed position, in which it remains under such tension that its bolt-carrying portions have a 95 100

tendency to move downwardly. Thus, when the bolts 13 are withdrawn and lie upon the flared wall portion 10 as seen in Fig. 3, the resiliency of the ring 14 will insure that the entire device shall remain in place. Normally, when the cover is not in use, the bolts 13 remain about as shown in Fig. 3, being then above the openings 11. When the cover is applied however, and the bolts 13 are 10 grasped by hand and forced downwardly upon the flared wall portion 10, this wall portion crowds the bolts inwardly, thereby placing the ring 14 under radial tension. This tension acts, as soon as the bolts arrive at the 15 registering openings 7-11, to outwardly project the bolts through said openings to the positions shown in Fig. 1, in which positions they will effectively hold the can cover 8 against accidental removal even though the 20 can 4 should be turned over.

While the bolts 13 are only loosely received in the openings 7-11, they are provided with teeth 15 which become effective upon slight upward shifting of the cover 8, 25 to positively prevent withdrawal of the bolts. These teeth then engage the walls of the openings 7 in the present disclosure, but they might be so positioned as to engage the walls of the openings 11 or the walls of all of the 30 openings 7-11. By providing these teeth, if anyone attempts to lift the can 4 by means of the handle 12, upward shifting of the cover 8 takes place, thereby somewhat canting the bolts 13 and causing their teeth 15 to 35 become immediately effective to prevent possible inward sliding of the bolts. This same action will take place if the can is tipped over and the milk or cream within exerts strong outward pressure upon the cover 8.

40 In the construction so far described, cast metal heads 16 on the inner ends of the bolts 13, are employed to anchor said bolts to the ring 14, said heads being cast about portions of bolts and ring. These heads are preferably 45 of about the same diameter as the openings 7-11, and if so desired, the bolts 13 may be canted from the positions shown in Fig. 1 and forced further outward, so that their heads 16 will be snugly received in the openings 7-11.

50 In Fig. 4, the toothed bolt 13^a is formed from sheet metal bent into tubular form and provided at its inner end with two lateral oppositely projecting lugs 16^a. These lugs and the adjacent portions of the tubular bolts 13^a are formed with openings 16^b. The spring ring is formed of two sections 14^a having eves 14^b on their ends engaged with the 55 openings 16^b.

60 By providing the novel construction shown and described or the equivalent thereof, a device is provided which is simple and inexpensive, may be easily applied to or removed from the can cover, may be quickly and easily 65 disposed at either locked or released position

and will be generally desirable in preventing accidental removal of milk and cream can covers.

Excellent results have been obtained from the details disclosed and they are therefore 70 preferably followed. However, attention is again invited to the fact that within the scope of the invention as claimed, variations may be made.

I claim:

1. A can cover lock comprising a spring metal ring for reception within the cover, and two bolts connected with and projecting outwardly from diametrically opposed portions of said ring for passage through openings in the cover and the can neck. 75

2. A can cover lock comprising a spring metal ring for reception in the cover, and two elongated bolts having enlarged cylindrical heads for passage through openings in the cover and the can neck, said bolts projecting radially from diametrically opposed portions of said ring and having their heads connected with the latter. 80

3. In combination with a can cover having a continuous side wall flared at its upper portion, a diametrically extending handle secured to said wall, and diametrically opposed openings through said flared wall portion at opposite sides of said handle, two bolts for passage outwardly through said openings, and resilient means passing under and held in downwardly bowed condition by said handle, said means carrying said bolts in substantially radial positions with their outer end above said openings and resting on said flared wall portion, whereby downward forcing of the bolts will effect inward shifting thereof to radially tension said resilient means and cause the latter to outwardly force said bolts when they reach said openings. 90

4. In combination with a can cover having a continuous side wall flared at its upper portion, and a diametrically extending handle secured to said wall, the latter having openings at opposite sides of said handle; a resilient ring within the confines of said wall and passing under said handle, and radially projecting bolts secured to said ring for passage outwardly through said openings. 95

5. In combination with a can neck and a cover receivable in said neck, the two having aligned openings; a bolt of considerably less diameter than said openings and adapted for passage therethrough, and spring means exerting a force tending to hold the bolt in the openings, said bolt having teeth to engage the wall of at least one of said openings upon slight upward movement of the cover to then positively hold said bolt against withdrawal. 100

In testimony whereof I have hereunto affixed my signature.

CLIFFORD E. ANDERSON.
